Primary Examiner — April Rivas*Assistant Examiner* — Jillian Mazzola(74) *Attorney, Agent, or Firm* — Carlson, Gaskey & Olds, P.C.(57) **CLAIM**

I claim the ornamental design for a hook tool, as shown and described.

DESCRIPTION

FIG. 1 is a perspective view of a hook tool showing the new design.

FIG. 2 is a top view of the hook tool.

FIG. 3 is a perspective side view of the hook tool.

FIG. 4 is a first end view of a first hook end of the hook tool; and,

FIG. 5 is a second end view of a second hook end of the hook tool.

1 Claim, 2 Drawing Sheets# US D1,032,185 S
